UNITED STATES PATENT OFFICE.

WILLIAM G. STEWART, OF CLEVELAND, OHIO.

SINK CONNECTION.

980,848.

Specification of Letters Patent.

Patented Jan. 3, 1911.

Application filed October 9, 1905, Serial No. 281,888. Renewed June 22, 1910. Serial No. 568,405.

To all whom it may concern:

Be it known that I, WILLIAM G. STEWART, residing at Cleveland, in the county of Cuyahoga and State of Ohio, have invented a certain new and useful Improvement in Sink Connections, of which the following is a full, clear, and exact description, reference being had to the accompanying drawings.

So far as I am aware, the universal manner of securing strainers in place above the waste pipe connections for sinks is to provide a pair of diametrically opposed openings in the strainer plate, near the periphery thereof, and to insert bolts therein, said bolts extending through openings provided in the bottom of the sink at the edge of the funnel-shaped outlet provided therein. The lower ends of these bolts pass through lugs or wings projecting from a concave annular disk which surrounds the upper end of the lead bend, nuts being provided for the lower ends of said bolts, by the tightening of which the strainer is held in place and the upper end of the lead bend is supported in operative relation to the outlet. In forming such bolt openings in the bottoms of modern enameled sinks, it frequently happens that the enamel is cracked, thereby spoiling the entire sink bottom, resulting in considerable waste of time, labor, and material.

The object of my invention is to provide a new connection between the sink bottom and the lead bend, whereby the strainer may be secured in place without the necessity for perforating the bottom of the sink and a simple and effective connection between such bottom and the lead bend may be secured. I accomplish these objects by the construction illustrated in the drawings, 40 wherein:

Figure 1 represents a vertical sectional view through the outlet of a sink bottom, the strainer, the waste pipe, and the connection which I employ between said outlet and waste pipe; and Fig. 2 represents a plan view of the parts shown in Fig. 1, a portion of the top of the strainer being broken away.

Describing the parts by reference numerals, 1 represents a portion of the bottom of a sink of ordinary construction, said bottom having a coating of enamel 1^a, and 2 the funnel-shaped outlet therefrom. At its periphery, the outlet 2 is provided with a ledge 3 forming a seat for the strainer 4. 5 55 denotes a short length of pipe of brass or similar material capable of retaining a

thread, said pipe being provided at its upper end with a funnel-shaped inlet 6 adapted to fit within the correspondingly-shaped outlet 2. Below the junction of the flaring 60 or funnel-shaped inlet 6 with the body of the pipe, the exterior of said pipe is provided with a screw thread 7, for the reception of a nut 8, the upper face of which is adapted to engage the lower end of the funnel 2, drawing the upper flaring end of such pipe into engagement with the inner surface of said funnel 2. In order to form a tight joint, any suitable packing material 9, such as white lead or putty, may be inserted 70 between such surfaces.

In order to secure the strainer in place, the upper end of the connection 5 is provided with a pair of lugs 10 projecting inwardly from the periphery thereof, said lugs being 75 preferably diametrically opposed to each other. Each of said lugs is provided with a threaded bore 11 for the reception of the lower end of a screw 12, which extends through a corresponding perforation 13 in 80 the strainer. The heads of the screws are preferably flat, whereby they may be flush with or slightly countersunk from the upper surface of the strainer.

To make a proper connection between the 85 pipe 5 and the upper portion 15 of the lead bend or waste pipe, I make use of the following construction:—A sleeve 16 is provided near the lower end thereof with a squared projection 17 for the application of 90 a wrench. At its upper end, said sleeve is provided with an exterior screw thread 18. The interior of said sleeve is beveled or flared outwardly toward the top to provide a tapered seat 19 for the upper end of the 95 lead waste pipe. 20 designates a gland comprising an inwardly projecting shoulder 21 adapted to loosely surround the pipe 5, and 22 represents the depending skirt of said gland provided with an interior thread 23 100 adapted to engage the exterior thread 18 on the sleeve 16. In assembling, the gland 20, having therein one or more packing rings 25, is slipped over the lower end of the pipe 5. The sleeve 16 is slipped over the upper end 105 15 of the lead waste pipe, and said upper end is then flared outwardly at 24, as shown in Fig. 1, to bring its upper end into substantial engagement with the tapered surface 19 of said sleeve. The gland 20 is then 110 screwed down upon the upper end of the sleeve 16, forcing the packing ring or rings

- into engagement with the upper end 15 of the waste pipe. These rings should closely fit the outer surface of the pipe 5. Two such rings are shown, the upper one being flat 5 and adapted to be engaged by the shoulder 21, the lower one being tapered to engage the outwardly flaring surface 24 of the waste pipe. By simply tightening on the gland 20 the lower tapered ring is forced 10 into the upwardly flared portion 24 of the lead pipe and a tight joint is formed between the pipe 5 and the upper end 15 of the lead waste pipe whereby any leakage between said parts is avoided.
- 15 By the construction herein described, it will be apparent that I am enabled to secure the strainer in place without the necessity for providing holes in the bottom of the sink and at the same time I am enabled to form 20 a tight connection between the sink and the lead waste pipe.
- Having thus described my invention what I claim as new and desire to secure by Letters-Patent is:—
- 25 1. The combination, with the outlet of a sink, of a leaden waste pipe therefor having its upper end flared outwardly, a tubular connection of rigid material the lower end whereof is of less diameter than the upper 30 end of the waste pipe and projecting into the upper end of the waste pipe, a gland surrounding said connection and having a depending interiorly threaded sleeve and an inwardly projecting shoulder, a sleeve sur- 35 rounding the upper end of the leaden waste

pipe and extending along the same and having the inner surface formed with a long outward flare and having its upper end provided with an external thread for engagement with the thread on the gland sleeve, 40 and packing interposed between the gland shoulder and the upper end of the leaden pipe and extending into the space between the flared end of the said leaden waste pipe and the tubular connection. 45

2. A pipe coupling comprising a lead pipe having its end flared outwardly, a tubular connection of rigid material the end of which is of less diameter than the bore of the lead pipe and projecting into the flared 50 end thereof, a gland nut surrounding said connection and having an interiorly threaded sleeve and an inwardly projecting shoulder, a sleeve surrounding the end of the lead pipe and extending along the same and having a portion of its inner surface shaped to surround the flared end of said lead pipe, said sleeve being provided with an external thread for engagement with the thread on the gland nut, and packing interposed be- 55 tween the shoulder of the gland nut and the flared end of the lead pipe and extending into the space between the flared end of the lead pipe and the tubular connection.

In testimony whereof I affix my signature 60 in the presence of two witnesses.

WILLIAM G. STEWART.
